UNITED STATES PATENT OFFICE

ISIDOR COWEN, OF NEW YORK, N. Y.

DESIGN FOR A DOLL OR SIMILAR ARTICLE

Application filed June 29, 1931. Serial No. 40,364. Term of patent 7 years.

To all whom it may concern:

Be it known that ISIDOR COWEN, citizen of the United States and resident of New York city, in the county of New York and State of New York, has invented a new, original, and ornamental Design for Doll or Similar Article, of which the following is a specification, reference being had to the accompanying drawings, forming part thereof, in which,

Fig. 1 is a front elevational view of a doll embodying my new design; and

Fig. 2 is a side elevational view thereof.

I claim:

The ornamental design for a doll or similar article, substantially as shown.

Dated June 26, 1931.

ISIDOR COWEN.
